UNITED STATES PATENT OFFICE.

JOHN ERNEST MILLER, OF BIRMINGHAM, PENNSYLVANIA, ASSIGNOR TO
SWEENEY, McCLUNEY, & CO., OF WHEELING, WEST VIRGINIA.

DESIGN FOR THE ORNAMENTATION OF GLASSWARE.

Specification forming part of Design No. 5,261, dated September 12, 1871.

To all whom it may concern:

Be it known that I, JOHN ERNEST MILLER, of Birmingham, in the county of Huntingdon and State of Pennsylvania, have invented and produced a new and original Design for Ornamentation of Glassware, of which the following is a description, reference being had to the accompanying drawing, which represents my design applied to a drinking-glass.

The nature of my design for ornamentation of glassware consists in waved lines extending

around the ware, as shown in the drawing annexed.

I claim as my invention—

The design for the ornamentation of glassware, as shown.

Witness my hand in matter of my application for a patent for seven years for a design for the ornamentation of glassware.

Witnesses: JOHN ERNEST MILLER.
